UNITED STATES PATENT OFFICE.

JOHN B. DANIELS, OF NEWTON CENTER, MASSACHUSETTS.

ADVERTISING DEVICE.

No. 825,195.

Specification of Letters Patent.

Patented July 3, 1906.

Application filed January 12, 1906. Serial No. 295,712.

To all whom it may concern:

Be it known that I, JOHN B. DANIELS, a citizen of the United States, residing at Newton Center, county of Middlesex, and State of Massachusetts, have invented an Improvement in Advertising Devices, of which the following description, in connection with the accompanying drawings, is a specification, like numerals on the drawings representing like parts.

This invention relates to that class of advertising devices in which the advertisement appears on a traveling web, sheet, or apron, which is given an intermittent motion to bring the various advertisements appearing on the web successively in front of an opening or aperture through which they are seen.

One embodiment of my invention will now be described and then the particular features of the invention will be pointed out in the claims.

In the drawings, Figure 1 is a front view of an apparatus embodying my invention. Fig. 2 is a side view thereof. Fig. 3 is a detail showing the way in which the web is wound up on the rolls. Fig. 4 is a top plan view of the gearing for driving the web. Fig. 5 is a detail of the driving means for one of the rolls; and Fig. 6 is a section on the line $x-x$, Fig. 5.

The web or apron on which the advertisements appear is designated by 3, and its ends are wound up onto two rolls 4 and 5, which are mounted in suitable bearings 6, carried by the supporting-frame 7. The web passes over direction-rolls 8 and 9, which are also driving-rolls, as will be presently described. The rolls 8 and 9 are driven from a vertical shaft 10, mounted in suitable bearings 11, and said shaft carries at its upper end a bevel-gear 12, which meshes with and is driven by a bevel-gear 13 on a counter-shaft 14. The shaft 14 is driven by gearing which is constructed to give it an intermittent motion and also to reverse its direction of motion at predetermined intervals. To accomplish these results, I have provided said shaft with two bevel-gears 15 and 16, which are loosely mounted thereon and either of which may be clutched to said shaft by a sliding clutch member 17. The gears 15 and 16 are driven by a gear 24 slidably mounted on a driving-shaft 25, which shaft is continuously rotated in one direction by means of a suitable motor 26 of any suitable construction. As herein shown, the shaft of the motor has a worm 27, which meshes with and drives a worm-gear 28 on a shaft 29, and fast to the shaft is a pinion 30, which meshes with and drives a gear 31 on the driving-shaft 25. When the gear 24 is in mesh with the gears 15 and 16, the latter gears rotate in opposite directions, as will be obvious, and the direction which the web or apron 3 travels depends on which gear, 15 or 16, is clutched to the shaft 14.

The gear 24 is alternately thrown into and out of mesh with the gears 15 and 16, thereby giving to the web 3 an intermittent motion. To accomplish this, I have provided the hub of the gear 24 with a groove 300, in which is received the forked end of a lever 311, which is acted upon by a suitable spring 32, that tends normally to disengage the gear 24 from the gears 15 and 16. Mounted on the driving-shaft 25 is a worm 33, which meshes with a worm-gear 34, and rigid with said gear is a cam member 35, which is adapted to engage one end of a thrust member 36, connected to the lever 311. During each rotation of the worm-gear 34 the cam member 35 engages the thrust member 36 and throws the gear 24 into mesh with the gears 15 and 16, as will be obvious, and when this occurs the shaft 14 is rotated in one direction or the other, dependent upon which gear, 15 or 16, is connected thereto. When the cam 35 passes out from under the end of the thrust member, the spring 32 disengages the gear 24 from the gears 15 and 16, thus disconnecting the motor from the counter-shaft and permitting the apron 3 to remain at rest. As soon as the gear 34 completes its revolution, however, and brings the cam 35 into engagement with the thrust member again, the counter-shaft will be again connected to the motor and the sheet 3 moved forwardly, as will be obvious. It will thus be seen that the sheet 3 has an intermittent movement, so that successive advertisements thereon may be brought into view. When the sheet has been entirely unrolled from one of the rolls 4 and 5 onto the other, the clutch 17 is automatically shifted to reverse the direction of movement of the counter-shaft 14. This is accomplished by means of a worm 23, fast on the shaft 14, which meshes with a worm-gear 22, carrying a pin 21, adapted to engage an arm 20, mounted on a rod 19, and preferably having a resilient end 220. This rod is connected to the clutch-shifting lever 18, by which the clutch 17 is shifted.

The worm and gear 22 and 23 are so proportioned that the gear 22 will make one

revolution during the time that the sheet or web is wound from one roll completely onto the other, and when this is accomplished the pin 21 engages the arm 20, thereby shifting 5 the clutch 17 and reversing the direction of movement of the counter-shaft 14. It will thus be seen that I have provided an automatic mechanism for intermittently moving the web 3 and for reversing said web when it 10 has been completely wound from one roll onto the other.

In order to keep the web 3 taut as it is wound from one roll 4 or 5 onto the other and to make it travel at a uniform speed, I prefer- 15 ably employ the rolls 8 and 9 as driving-rolls and provide friction mechanism for driving the rolls 4 and 5. In this way the sheet 3 may be given a uniform motion regardless of the amount wound on either of the rolls 4 or 20 5. As herein shown, the rolls 8 and 9 are mounted on shafts 40 and 41, and each shaft has fast thereon a skew-gear 42, meshing with a corresponding skew-gear 43, fast on the shaft 10. Loosely mounted on the shaft 25 41 is a sprocket-wheel 47, which is connected by a suitable sprocket-chain with a sprocket-wheel 48, loose on the roll 4. The sprocket-wheel 47 carries a pawl 49, adapted to engage a ratchet 50, fast on the shaft 41, said pawl 30 and ratchet being so arranged that as the roll 9 is rotated clockwise in Fig. 3, or in a direction to carry the sheet 3 upwardly, the sprocket-wheel 47 will be driven, and consequently the sprocket-wheel 48. The 35 sprocket-wheel 48 has a frictional engagement with the roll 4 sufficient to drive the latter to cause the sheet 3 to be wound up thereon; but when the sheet is nearly wound onto the roll 4, as shown in Fig. 2, so that the 40 normal rotation of said roll would tend to draw the sheet faster than it is fed by the driving-roll 9 the sprocket-wheel 48 may slip slightly. The frictional engagement between the sprocket-wheel 48 and the roll 4 is pro- 45 vided for by loosely mounting said sprocket-wheel on the shaft of the roll and providing said wheel with a friction-surface 500, which is yieldingly held against a friction-surface 51, fast with the roll, by means of a spring 52. 50 The sprocket-wheel 470 is also connected to the shaft 40 by a pawl-and-ratchet mechanism 53 54, which is disposed oppositely to that on the shaft 41, the pawl-and-ratchet mechanism 53 and 54 having such a construction 55 that when the shaft 40 is rotated in a direction to draw the sheet downwardly the sprocket-wheel 470 will be driven. The sprocket-wheel 470 is geared to a sprocket-wheel 56, having a frictional connection with the roll 5, 60 similar to that between the sprocket-wheel 48 and the roll 4 and for a similar purpose.

It will be obvious that although both the shafts 40 and 41 are positively driven, yet when they are rotating in a direction to feed 65 the sheet or web upwardly the sprocket-wheel

47 will be driven, and consequently the roll 4 will be rotated to wind the sheet thereon; but the sprocket-wheel 470 will be held from rotation by a suitable pawl 60, and consequently the sprocket-wheel 56 will be held 70 stationary. As the sheet or web is drawn from the lower roll 4 the stationary sprocket-wheel 56 with its friction-surface acts as a brake to hold the sheet perfectly taut. When, however, the direction of rotation of shaft 10 75 is reversed and the rolls 8 and 9 are rotated in a direction to feed the sheet downwardly the sprocket-wheel 470 will be positively driven, and through the sprocket-wheel 56 the roll 5 will be rotated to wind the sheet thereon. 80 During this time the sprocket-wheels 47 and 48 are held from rotation by means of a suitable stop-pawl 61, and the sprocket-wheel 48 then acts as a brake to hold the sheet 3 taut. The sheet is held against these driving-rolls 85 by suitable presser-rolls 70, which are yieldingly held against the sheet by means of suitable springs 71.

It will be seen that by reason of the special form of driving means I have employed for 90 the sheet 3 said sheet will always be kept taut without placing thereon sufficient strain to tear or injure it.

Having fully described my invention, what I claim as new, and desire to secure by Let- 95 ters Patent, is—

1. In an advertising apparatus, a continuously-rotating driving-shaft, a bevel-gear splined thereto, a counter-shaft having two bevel-gears loose thereon, means to move the 100 first-named bevel-gear longitudinally of the shaft to cause it to mesh with the last two bevel-gears, means to clutch either of said last two bevel-gears to the counter-shaft, a traveling web and web-moving means oper- 105 ated from the counter-shaft.

2. In an advertising apparatus, a continuously-rotating driving-shaft, a bevel-gear splined thereto, a counter-shaft having two bevel-gears loose thereon, automatic means 110 to cause the first-named bevel-gear to mesh with the two bevel-gears for definite periods of time at definite intervals, automatic means to clutch the last two bevel-gears alternately to the counter-shaft, a traveling web and 115 web-moving means operated from the counter-shaft.

3. In an advertising apparatus, a traveling web, means to drive it comprising a counter-shaft, two gears loose thereon, an automatic 120 clutch to alternately clutch the gears to said shaft, a driving-shaft, and automatic means to throw said last shaft alternately into and out of gear with the first-mentioned shaft.

4. An advertising device comprising a trav- 125 eling web, two separate driving-rolls over which said web passes and by which it is driven, a winding-roll associated with each driving-roll, means to rotate the driving-rolls, automatic means to reverse the direction of 130

rotation thereof, means to rotate one winding-roll from the corresponding driving-roll when the driving-rolls are rotating in one direction whereby the web is wound on said 5 winding-roll, means to rotate the other winding-roll from the corresponding driving-roll when said driving-rolls rotate in the opposite direction to rewind the web on the latter winding-roll, and means to retard the 10 winding movement of each winding-roll.

5. In an advertising apparatus, a traveling web, two driving-rolls over which it passes, two winding-rolls on which the web is wound, means for positively rotating the driving- 15 rolls, automatic means to reverse at stated times the direction of rotation thereof, a friction driving device between each driving-roll and the adjacent winding-roll, and means to lock the friction driving device of that winding-roll from which the web is being unwound. 20

6. In an advertising apparatus, a traveling web, two driving-rolls over which it passes, two winding-rolls on which the web is wound, means to rotate the driving-rolls first in one 25 direction, and then in the other, a friction

driving device between each driving-roll and the corresponding winding-roll, and a stop-pawl coöperating with each friction driving device to hold that one stationary which corresponds to the winding-roll from which the 30 web is being unwound.

7. In an advertising apparatus, a traveling web, two driving-rolls over which it passes, a winding-roll adjacent each driving-roll, a sprocket-wheel having pawl-and-ratchet connection with each driving-roll, another sprocket-wheel having a frictional connection with each winding-roll, a sprocket-chain connecting the sprocket-wheel of one driving-roll to that of the corresponding winding- 35 roll, and a stop-pawl to engage one sprocket-wheel of each pair.

In testimony whereof I have signed my name to this specification in the presence of two subscribing witnesses.

JOHN B. DANIELS.
